(57) **CLAIM**

The ornamental design for a adjustable yard trimmer, as shown and described.

DESCRIPTION

FIG. 1 shows a perspective view of an adjustable yard trimmer, showing my new design;

FIG. 2 shows a top plan view of the adjustable yard trimmer.

FIG. 3 shows a bottom plan view of the adjustable yard trimmer.

FIG. 4 shows a front elevation view of the adjustable yard trimmer.

FIG. 5 shows a rear elevation view of the adjustable yard trimmer.

FIG. 6 shows a left side elevation view of the adjustable yard trimmer.

FIG. 7 shows a right side elevation view of the adjustable yard trimmer; and,

FIG. 8 shows an alternative perspective view of the adjustable yard trimmer.

The broken lines shown in the Figures form no part of the claimed design.
